DESIGN FOR A BEAN POT

Chester C. Soule, Portland, Maine, assignor to Maine Canned Foods, Inc., Portland, Maine, a corporation of Maine

Application December 1, 1938, Serial No. 81,492

Term of patent 14 years

To all whom it may concern:

Be it known that Chester C. Soule, a citizen of the United States, residing at Portland, in the county of Cumberland and State of Maine, has invented a new, original, and ornamental Design for a Bean Pot, of which the following is a specification, reference being had to the accompanying drawing, forming part thereof, wherein:

Figure 1 is a perspective view of a bean pot
showing my new design.

Figure 2 is a side elevation, and Figure 3 is a top plan view.

I claim:—

The ornamental design for a bean pot, as shown.

CHESTER C. SOULE.
